[57] ABSTRACT

A self-leveling apparatus which has a support table movably mounted for upward and downward movement between two vertical supports attached to the base of the cart; cables attached to the support table and to a rotatable shaft mounted in the base of the cart; a coiled torsion spring mounted concentrically with the shaft and having one end operatively connected thereto for regulating the rotation of the shaft in relation to the objects placed on or removed from the support table; and a slider bar on a guide bar adjustable along the length of the torsion spring, whereby positioning of the slider bar along the guide bar will determine the effective length of the torsion spring and, accordingly, the torsion of the spring, so that when objects of varying weights are placed on the support table, the torsion spring can be adjusted to provide the correct torque to keep the support table at a constant height no matter what the per unit weight of the objects added to or removed from the support table may be.

HANDCART

The present invention relates to a handcart comprising a support table on which articles to be handled are placed either as arranged in a plurality of layers (each layer may consist of a plurality of articles regularly arranged in a common plane) or as received in a plurality of baskets, and a spring adapted to function in such a manner that the uppermost layer of articles or basket placed on said support table has its level (or height as measured from the floor) maintained substantially constant regardless of whether articles are unloaded from or loaded upon said support table.

Among such handcarts heretofore known is a type of handcart comprising a torsion spring having one end thereof fixed relative to the cart base of the handcart and the other end operatively connected to the support table so that the support table may stop at a position where the weight of the articles placed on the support table is balanced by the restoration force of said torsion spring.

In this type of handcart, when the per unit weight of one layer of articles or the total weight of the articles contained in one basket is changed, it is necessary to adjust the distance of upward and downward movement of the support table per unit weight. To this end, the conventional practice has been to impart a selected amount of torsion to the torsion spring in advance and then fix said one end relative to the cart base. With such arrangement, however, although the weight required to initially move the support table can be adjusted, once the support table starts to move, the distance of upward and downward movement of the support table per unit weight is substantially no different from what it had been before the torsion spring was adjusted.

The present invention has for its object to provide a handcart of the described type providing an adjustable distance of upward and downward movement of the support table per unit weight.

Other objects and advantages of the present invention will appear as the description proceeds, when taken in conjunction with the accompanying drawings in which:

FIG. 1 is a front view of a handcart according to the present invention;

FIG. 2 is a side view of the handcart shown in FIG. 1; and

FIG. 3 is a sectional view taken along the line III-III of FIG. 2.

Like numerals indicate like parts or corresponding parts throughout the Figures.

Referring to the drawings, particularly FIGS. 1 and 2, a handcart according to the present invention comprises a cart base 1, right and left hollow pillars 2, 2, and a support table 3 movable up and down along said hollow pillars 2 in parallel relation to said cart base 1. The handcart is provided with wheels 4 and push handles 5 and 6 whereby it can be moved to any desired locations.

A housing 7 for receiving a torsion spring therein extends below the hollow pillars 2, 2 traversing of the cart base 1 and is removably secured in place. The internal construction of the housing is shown in detail in FIG. 3. The openings at opposite ends of the housing 7 are closed by the bent portions 8₁ and 8₂ of a support plate 8 removably but rigidly secured to the housing 7 by any

suitable means thereby preventing the entry of dust into the housing 7.

The support plate 8 is provided with bearings 9 and 10 adjacent opposite ends thereof and a shaft 11 is rotatably mounted in said bearings. Bearing holders 12, 13 are fixed to said support plate 8 to hold the bearings 9 and 10, respectively. Cable drums 14 and 15 are fixed on the shaft 11 adjacent opposite ends thereof by locking pins 16 and 17 so as to rotate together with the shaft 11. Cables 18 and 19 are wound around the cable drums 14 and 15, respectively, a necessary number of turns. One end of each of these cables is fixed to its associated cable drum 14, 15, and the other ends are passed around pulleys 20 and 21 rotatably mounted on the tops of the hollow pillars and are fixed to the support table 3.

The support plate 8 has a support bracket 22 welded or otherwise secured thereto, said bracket 22, in turn, having a spring support 23 welded or otherwise secured thereto. Further, another spring support 24 is secured to the shaft 11 by a pin 25 or any other suitable means so as to rotate together with the shaft 11. The opposite end portions of the torsion spring 28 are fitted over the sleeve portions 26 and 27 of the spring supports 23 and 24, respectively, and one end of said torsion spring 28 is fixed to one spring support 23 and the other end to the other spring support 24.

The operation of the handcart as described so far is as follows.

When there is no article placed on the support table 3, there is no load acting on the support table, thus the torsion spring 28 is in its completely restored condition with the support table 3 assuming its uppermost position. When articles are placed on the support table 3, the weight of the placed articles acts on the support table 3 to twist the torsion spring 28 through the cables 18, 19, cable drums 14, 13, shaft 11 and spring support 24. Thus, the support table 3 stops at a position where the restoration force produced in the torsion spring 28 is balanced with the weight of the article placed on the support table 3. As articles are successively placed on the support table 3, the support table 3 is lowered accordingly. Therefore, when articles are successively stacked in layers on the support table 3, the level of the uppermost layer of articles (or the height as measured from the floor) is maintained substantially constant. When the articles are successively unloaded from the support table 3, the support table 3 is correspondingly raised in such a manner that the level of the uppermost layer of articles again is maintained substantially constant. Therefore, the operator can do the loading and unloading of articles to and from the support table, respectively, in his comfortable posture.

However, even when articles having a different shape or weight are handled, it is often desirable to maintain the level of the uppermost layer of articles substantially constant. To this end, the present invention incorporates into the handcart a novel arrangement to be described hereinafter.

According to the present invention, a guide sleeve 29 is fixed to the support bracket 22 concentrically with respect to the shaft 11 and a slider 30 is slidably mounted on said guide sleeve 29. The outer diameter of the slider 30 is made to be equal to or slightly smaller than the inner diameter of the torsion spring 28 when there is no article placed on the support table. There is a threaded rod 31 parallel to the guide sleeve 29 for

moving the slider 30 along the guide sleeve 29, said threaded rod 31 being engaged with the internal threads 32 of the slider 30. Thus the rotation of the threaded rod 31 causes the slider 30 to move in a direction determined by the direction of said rotation. The threaded rod 31 is rotated from a rotatable shaft 33 which is rotated by means of a removable handle (not shown), through a bevel gear 34 secured to said rotatable shaft 33, a suitable gear train 35, 36, 37, 38 and a bevel gear 39 secured to the end of the threaded rod 31. Also included is a bearing 40 for the rotatable shaft 33; a bearing holder 41; and a washer 42.

In this connection, it will be noted that when the type of articles to be handled is changed, in order to maintain the level of the uppermost layer of articles substantially constant, it is necessary, as described above, to adjust the distance of up and down movement of the support table per unit weight. In this case, according to the present invention said handle (not shown) is fitted over the rotatable shaft 33 and is then rotated to rotate the threaded rod 31, whereby the slider 30 is moved along the guide sleeve 29 in a direction determined by the direction of rotation of the threaded rod 31 and by an amount corresponding to the amount of rotation of the threaded rod 31. Let it be assumed that the slider 30 has been moved, e.g. to the left as viewed in FIG. 3. As articles are placed on the support table 3, the torsion spring 28 is twisted resulting in a decrease of the inner diameter thereof, so that the torsion spring 28 is clamped onto the slider 30. Therefore, the torsion spring 28 is effectively fixed to the slider 30, and when articles are successively placed on the support table, the portion of the torsion spring 28 located on the right-hand side of the slider 30 as viewed in FIG. 3 is not twisted while only the left-hand side portion is twisted. This means that the effective length of the torsion spring 28 is decreased, so that the distance of up and down movement of the support table 3 per unit weight is decreased.

Conversely, when the slider 30 is displaced to the right as viewed in FIG. 3, the distance of up and down movement of the support table per unit weight is increased.

While a particular embodiment of the invention has been described, the invention is not limited thereto. For example, the spring support 23 may be removed and the fixing end of the torsion spring 28 may be fixed directly to the support bracket 22. The other end of the torsion spring 28 may be fixed with respect to the shaft

11 without using the spring support 24. Furthermore, the bearing 9 and the cable drum 14 may be changed in position thereof with each other so that said other end of the torsion spring 28 may be fixed to the cable drum 14. Still further, it is possible to omit the guide sleeve 29, and to arrange the slider 30 to be slidably movable directly on the shaft 11.

What is claimed is:

1. A self-leveling apparatus comprising:

a base;

hollow upright supports attached to and extending vertically from said base;

a shaft rotatably mounted in said base between said upright supports;

cable drums fixed to opposite ends of said shaft and rotatable therewith;

pulleys rotatably mounted at the top of said hollow upright supports;

20 a torsion spring arranged concentrically with respect to and at a distance away from said rotary shaft and having one end thereof fixed stationarily with respect to said base, and the other end fixed to said rotatable shaft;

a support table mounted between said hollow upright supports and movable vertically in a horizontal position parallel to said base;

cables having one end fixed to said cable drums extending upward through said hollow upright supports and over said pulleys, with the other end fixed to said support table;

30 a guide sleeve operatively located within the space between said torsion spring and said rotatable shaft;

a slider slidable on said guide sleeve within said space between the torsion spring and the shaft, the outer diameter of said slider fitting within the inner diameter of the torsion spring when there is no load on the support table; and

35 adjusting means for moving said slider along said guide sleeve within said torsion spring whereby adjusting the position of the slider by the adjusting means in relation to the torsion spring will regulate the effective length of the torsion spring.

2. A self-leveling apparatus as claimed in claim 1, wherein said adjusting means comprises a threaded rod onto which the slider is threaded and rotating means for rotating said threaded rod.
